US00D990841S

(12) **United States Design Patent** (10) Patent No.: **US D990,841 S**
(45) Date of Patent: **** Jul. 4, 2023**

(54) **FOOTWEAR**

(71) Applicant: **Crocs, Inc.**, Broomfield, CO (US)
(72) Inventor: **Sheila Kaufman**, Columbia, CT (US)
(73) Assignee: **Crocs, Inc.**, Broomfield, CO (US)
(**) Term: **15 Years**
(21) Appl. No.: **29/786,639**
(22) Filed: **Jun. 1, 2021**
(51) LOC (14) Cl. **02-04**
(52) U.S. Cl. **USPC D2/947**

(58) **Field of Classification Search**
